UNITED STATES PATENT OFFICE.

HENRY O. SCHMIDT, OF NEW YORK, N. Y., ASSIGNOR TO SIMONS, BROTHER & CO., OF PHILADELPHIA, PENNSYLVANIA.

DESIGN FOR A CANE OR UMBRELLA HANDLE.

SPECIFICATION forming part of Design No. 19,956, dated July 1, 1890.

Application filed April 15, 1890. Serial No. 348,103. Term of patent 3½ years.

To all whom it may concern:

Be it known that I, HENRY O. SCHMIDT, a citizen of the United States, residing in New York, in the county and State of New York, have invented and produced a new and original Design for Cane or Umbrella Handles, of which the following is a specification, reference being had to the accompanying drawing, forming part thereof.

10 In the drawing is shown a side elevation of a cane or umbrella handle illustrating my new design.

A is the lower part of the body, and extends up with a gradually-increasing diameter, spreading in one direction to form a crook B and in the other to form a heel C.

15 E is a V-shaped relief-line upon the sides of the handle, running from the rear end of the heel C toward the front end of the crook B, making the lower portion A act as a basket or support for the upper part G of the handle. The part G is rounded and appears to rest upon the upper part A above the band E, and as it approaches the front end of the crook 20 said part G is ornamented with the ribs H,

which as they approach the end of the crook become larger and larger. The portion marked G, adjacent to this ornamentation H, is shaded as indicated. The band E at its lowest point is run off into ornamentation, as indicated at F, 30 said ornamentation approximately covering the body part A. The body part A, the part G, and the crook B, with its ribbed work H, are of plain surface, but may be shaded or combinations of these effects.

35 D is the annular base band or rim to the body part A, and is highly ornamented.

The handle is made of any suitable material.

Having now described my invention, what 40 I claim as new, and desire to secure by Letters Patent, is—

The design for umbrella or cane handles, substantially as herein described and shown.

In testimony of which invention I have hereunto set my hand.

HENRY O. SCHMIDT.
